Primary Examiner — Elizabeth J Oswecki*(74) Attorney, Agent, or Firm* — Russell D. Nugent; The Humphries Law Firm, P.C.(57) **CLAIM**

The ornamental design for a golf shoe, substantially as shown and described.

DESCRIPTION

FIG. 1 is a top, left, front perspective view of a golf shoe showing our new design;

FIG. 2 is a bottom, right, back perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

FIGS. 1-8 illustrate a right golf shoe, with the left golf shoe being a mirror image thereof. The broken lines shown in the drawings represent portions of the golf shoe that form no part of the claimed design.
